UNITED STATES PATENT OFFICE.

CORNELIA L. BLAIR, OF WASHINGTON, DISTRICT OF COLUMBIA.

GARMENT-STAY.

1,179,156.

Specification of Letters Patent.

Patented Apr. 11, 1916.

Application filed June 22, 1915. Serial No. 35,801.

To all whom it may concern:

Be it known that I, CORNELIA L. BLAIR, a citizen of the United States, residing at Washington, in the District of Columbia, have invented certain new and useful Improvements in Garment-Stays; and I do hereby declare the following to be a full, clear, and exact description of the invention, such as will enable others skilled in the art 10 to which it appertains to make and use the same.

It has been the common practice in the art of corset manufacturing to employ various means of anchorage for the stiffening stays 15 of the garment, consisting chiefly and usually of stitching about the edges of the stays, and in some instances, through apertures in the stay, and it has even been proposed to provide retaining pins and tabs for holding 20 the stay in place, but, notwithstanding these endeavors, distressing difficulties arise in the use of corsets from the fact that the terminal portions of the stays persist in working loose and breaking through the surrounding fabric either laterally or longitudinally, incident to the continued flexing to 25 which the stay is subjected, which results both in the impartation of lateral vibratory movements to the terminals of the stay, and a creeping or longitudinal movement to the 30 entire stay. The result is that great difficulty has been experienced in endeavors to prevent the stays from working through the cloth and protruding at either one or both ends of the garment, where they frequently painfully injure the flesh of the wearer.

To overcome these difficulties, is the primary object of this invention, and to this end, the invention comprises a means of 40 anchorage intended to obviate independent vibratory movement of the terminal portions of the stay with respect to the surrounding fabric and to, at the same time, prevent longitudinal creeping of the stay.

45 More in detail, the invention comprises spring clips fixed to a stay and located to engage adjacent portions of fabric and thereby cause the fabric and stay to be held against relative independent movement.

50 The invention comprises certain other novel constructions, combinations and arrangements of parts as will hereinafter be specified and claimed.

55 In the accompanying drawing: Figure 1 is a view in side elevation of a stay embodying the features of the present invention.

Fig. 2 is an edge view thereof, parts being seen in vertical section. Fig. 3 is a perspective view of a fragment of the stay seen in its applied condition relative to the fabric of 60 a corset. Fig. 4 is a greatly enlarged detail perspective view of a clip detached.

Referring to the drawing by numerals, 1 indicates a stay, which may be of any of the well known forms. To the end portions of 65 stay 1 are fixed spring clips 2, each of which clips is a duplicate of all the others, and one clip will, therefore, be described in detail and the description is applicable to all. The clip consists of an eye 2', having a 70 spring tongue bent at 2" to form an eyelet receiving loop portion and extending at 2" beyond the loop 2" in the form of a flat straight portion adapted to lie flat against the face of the stay 1. The loop portion 2" 75 not only serves to receive an eyelet in use, as will hereinafter appear, but also serves to insure the retention of the flat extended portion 2" in intimate contact with the surface engaged, so that the free terminal of 80 the portion 2" is not given any tendency to curve outward, and is held normally perfectly flat against the face of the stay or against the face of the fabric interposed between the clip and the stay. Each clip 2 is 85 preferably of appropriate spring metal, and is rendered free from rough or cutting edges either by having all edges rounded off or by having the clip enameled. The eye 2' is engaged by a rivet 3 which extends through the stay 1 and is peened at each end to as 90 nearly flat condition as possible, being preferably flattened into a countersink space formed in the stay and eyelet at the respective ends of the rivet. 95

The main fabric of the corset is indicated, in Fig. 3, at 4, overlaid by an outer piece of fabric or stay casing 5. The stay 1 may be disposed in a longitudinal casing on the corset in the usual manner or otherwise arranged with respect to fabric 4 as preferred, but whatever the arrangement may be, the fabric 5 is caused to be engaged by the several clips 2 after the manner indicated in Fig. 3. The said fabric 5 is provided with eyelets 6, 6, preferably of elongated form and of a size to snugly receive the respective spring clip. Each eyelet 6 is rounded about its edges so as to produce no rough or cutting edges and may be enameled like the clip. The eyelets 6 at each end portion of the stay 1 are spaced apart 100 105 110

2
a distance equal as nearly exactly as possible to the distance apart of the shoulders of loops 2" nearer the eyelets 2', so that when the fabric 5 is being positioned with respect to clips 2, it must be crimped or gathered longitudinally until the eyelets 6 can be passed over the free ends of the clips 2 and then the fabric 5 is straightened out so that the eyelets 6 assume the final position indicated in Fig. 3 in firm engagement with the shoulders of the loops 2". Thereupon, the fabric 5 is stitched to the corset fabric 4, as at 7, forming lines of stitching extending along the edges of the stay 1. The casing 5 may also be stitched across the ends as at 7', this stitching being sufficiently spaced from the ends of the stay to allow of a reasonable amount of play of the terminals of the stay. The parts having thus been caused to assume the position seen in Fig. 3, the clips 2 rest firmly against the outer face of the fabric 5 and press it against the stay, and positively retain the stay from excessive independent vibratory movement, and from any longitudinal creeping in either direction. The ends of the stay are free to have such lateral play as necessary incident to flexing of intermediate portions of the stay in use.

30 The rivets for clips 2 and the material of stay 1 will be proportioned to have the requisite dimensions to insure against loosening of the rivets.

What I claim is:

- 35 1. The combination, with a garment stay, of a clip fixed at one end to the stay and having a spring tongue extending along the stay and flat against the same for a portion of its length, a portion of the tongue being looped outward from the stay, the tongue being flat throughout its length except for the loop.
2. The combination, with a garment stay, of a clip fixed at one end to the stay and having a flat spring tongue extending along the stay and flat against the same for a portion of its length, that portion of the tongue adjacent the fixed end of the clip being formed into an outstanding loop.
- 50 3. The combination, with a garment stay, of a clip fixed at one end to the stay and having a flat spring tongue extending along the stay and flat against the same for a portion of its length, that portion of the tongue adjacent the fixed end of the clip being formed into an outstanding loop, the
- 55

clip being formed with rounded edges so as to present no sharp or cutting edges to contiguous fabric.

4. The combination, with a garment stay, 60 of a spring clip, and a rivet extending through the stay and clip and fixing the clip to the stay, the stay being formed with a free spring tongue portion extending along the stay and disposed to receive and clamp fabric between itself and the stay, the clip being shaped to retain its fabric engaging portion substantially flat against the engaged surface of the fabric.

5. The combination, with a garment stay, 70 of clips fixed to the stay adjacent one of the end portions thereof and each comprising a spring tongue extending along the stay toward the other clip, a portion of each of the tongues being adapted to lie 75 flat against the face of the stay or the engaged face of fabric interposed between the stay and the tongue.

6. The combination, with a garment stay, 80 of a spring clip fixed to the stay adjacent its upper end portion and extending longitudinally of the stay downwardly, and a similar clip spaced downwardly from the first clip and fixed to the stay and extending upwardly along the stay, each clip comprising a tongue disposed to lie flat against the stay or against the engaged surface of fabric interposed between the stay and clip, an intermediate portion of the tongue of each clip being formed into an eyelet receiving loop.

7. The combination, with a garment stay, 85 of a spring clip fixed to the stay adjacent its upper end portion and extending longitudinally of the stay downwardly, and a similar clip spaced downwardly from the first clip and fixed to the stay and extending upwardly along the stay, each clip comprising a tongue disposed to lie flat against the stay or against the engaged surface of 100 fabric interposed between the stay and clip, an intermediate portion of the tongue of each clip being formed into an eyelet receiving loop, and a pair of similar clips relatively similarly located on the stay at the 105 lower end portion thereof.

In testimony whereof I affix my signature in presence of two witnesses.

CORNELIA L. BLAIR.
